UNITED STATES PATENT OFFICE.

HERMAN E. DE PEW, OF ALAMEDA, CALIFORNIA.

ANTPROOF SHELF BRACKET.

Application filed August 5, 1926. Serial No. 127,326.

The invention relates to brackets for supporting shelves and the like, and has for its object the provision of means to prevent ants and other crawling insects from reaching the shelf or other object supported by the bracket.

Another object of the invention is the provision of a shelf bracket having a downwardly directed portion, and a container to receive said downwardly directed portion, said container being adapted to hold a liquid to prevent insects from crawling along the bracket to reach the article supported thereby.

Another object of the invention is the provision of an improved shelf bracket consisting of a grooved member adapted to be secured to a suitable support by being engaged with a pointed threaded end of a bracket arm, said bracket arm having a U-shaped depressed portion intermediate of its ends, one of the sides of said U-shaped portion being received by the grooved member, and providing a container to receive the downwardly directed U-shaped portion and having a groove in the wall to fit between the side of the U-shaped portion of the arm and the groove member to hold it in position, said container being adapted to receive a liquid to prevent insects from crawling along the arm to reach the object supported thereby.

The invention will be described in detail hereinafter and will be found illustrated in the accompanying drawings in which

Figure 1 is a side view in elevation of the improved ant-proof shelf bracket,

Figure 2, a front view,

Figure 3, a vertical sectional view on a plane indicated by the line 3—3 of Figure 2,

Figure 4, a transverse sectional view on a plane indicated by the line 4—4 of Figure 2, and

Figure 5, a detail of the grooved member.

In the drawings similar reference characters will be used to designate corresponding parts throughout the several views.

The improved shelf bracket comprises an arm 1 having one of its ends pointed and threaded as shown at 2 to engage a suitable support A, while its other end is formed with an upright lug 3 and a contiguous shoulder 4 to support a shelf or other article to be spaced from the support A. Intermediate of the ends of the arm 1 is a U-shaped downwardly directed portion 5, having one of its sides 6 arranged contiguous to

the support A when in position. 7 designates a plate having an opening 8 adjacent to its upper end to receive the pointed and threaded end 2 of the arm 1 to hold it in position on the support A, and an opening 9 adjacent to its lower end to receive a driven fastening 9^a engaging the support A. Intermediate of the ends of the plate 7 the sides are turned outwardly as shown at 10 to enclose the side 6 of the downwardly directed portion 5 and to form therewith a clamping member to secure a container 11 in position, said container being provided with a pressed in vertical groove 12 to slip between the side 70 6 of the downwardly directed portion 5, and the walls of the groove formed by the outwardly directed members 10.

In use, the article is assembled as shown in the drawings and water or other liquid, 75 such for instance as an insecticide, may be placed in the container 11. It will be apparent that ants or other crawling insects cannot reach the article supported on the lug 3 because of the liquid in the container 11, 80 and the food or other articles supported on the shelf mounted on the arm would be protected from inroads by such insects. It will also be apparent that the container 11 is held frictionally between plate 7 and side 6 85 of the arm 1 so that it may be removed when desired for cleaning or for any other purpose.

What is claimed is:—

1. A shelf bracket, including a U-shaped 90 member, an arm extending at an angle to one of the sides of the member and adapted to engage a support, the other side of the member formed to support a shelf, and a cup shaped container the vertical wall of 95 which frictionally engages between the U-shaped member and the support and to hold a liquid immersing the member.

2. A shelf bracket, including a U-shaped member, a threaded arm extending at an angle to one of the sides of the member to engage a support, a lug on the extremity of the other side of the member, a shoulder contiguous to said lug, said lug and shoulder being adapted to support a shelf, and a cup shaped container for liquid to receive the U-shaped member and the vertical wall of which frictionally engages between the U-shaped member and the support. 105

3. A shelf bracket, comprising a grooved 110 clamping member, an arm having one of its terminals adapted to secure said member to

a support, a lug on the other terminal of said arm to engage a shelf, a horizontal shoulder on the arm adjacent to said lug to support the shelf, a U-shaped portion intermediate of said shoulder and the first mentioned terminal of the arm, one of the sides of said U-shaped portion received by the grooved member, and a cup shaped con-

tainer to receive said U-shaped portion and having an offset groove in its vertical wall to engage between the grooved member and the side of the U-shaped portion, said container adapted to hold a liquid. 10

In testimony whereof I affix my signature.

HERMAN E. DE PEW.
